RADIO RECEIVER

Ken Kawamura, Osaka, Japan, assignor to Matsushita
Electric Industrial Co., Ltd., Kadoma-shi, Osaka, Japan

Filed June 28, 1972, Ser. No. 266,921

Claims priority, application Japan Dec. 29, 1971

Term of patent 14 years

Int. Cl. D14—03

U.S. Cl. D56—4 B

FIG. 1

FIG. 2

FIG.3

FIG.4

FIG.5

FIG.6

FIG. 1 is a front, top, right hand perspective view of a radio receiver showing my new design, with the retractable handle in raised position, the pivotable, extendable aerial in depressed, locked position, and a removable rear cover in place,

FIG. 2 is a rear, bottom, left hand perspective view thereof,

FIG. 3 is a front, top, left hand perspective view thereof with the rear cover removed, the handle depressed, and the aerial pivoted to a slightly raised position and partially extended,

FIG. 4 is a front, top, right hand perspective view of the cover removed from the rear of the radio receiver of FIG. 1,

FIG. 5 is a rear, top, left hand perspective view of the cover of FIG. 4 forming a part of the radio receiver of FIG. 1, and

FIG. 6 is a rear, top, right hand perspective view of the radio receiver of FIG. 3 with the cover removed, the handle depressed, and the aerial partially raised and partially extended.

I claim:

The ornamental design for a radio receiver, as shown and described.
